UNITED STATES PATENT OFFICE.

BROR MAX SCHAUMAN, OF PHILADELPHIA, PENNSYLVANIA, ASSIGNOR TO UNION BRISTLE AND FIBER COMPANY, OF NEW YORK, N. Y., A CORPORATION OF NEW YORK.

MACHINE FOR COMBING BRISTLES.

SPECIFICATION forming part of Letters Patent No. 747,650, dated December 22, 1903.

Application filed April 7, 1903. Serial No. 151,427. (No model.)

To all whom it may concern:

Be it known that I, BROR MAX SCHAUMAN, a subject of the King of Sweden and Norway, residing at Philadelphia, in the county of 5 Philadelphia and State of Pennsylvania, have invented certain new and useful Improvements in Machines for Combing Bristles, of which the following is a specification.

My invention consists of a machine for 10 moving short stock from bristles—that is to say, combing out from a mass of bristles fed to the machine all bristles which are not of sufficient length to be of value to the brush-maker. In addition to this my machine is 15 adapted to the removal of fine woolly hair which is intermingled with the bristles and which is of no value to the brush-makers and which must therefore be removed if it is desired to enhance the value of the finished 20 product.

The nature of my improvements will be best understood by reference to the following drawings, in which—

Figure 1 illustrates a side elevation of my 25 machine; Fig. 2, a plan view of the same; Fig. 3, an end elevation of the machine as viewed from the left-hand side. Figs. 4, 5, and 6 are diagrammatic views showing the paths taken by the main belts and two binder-belts; and Fig. 7 is a perspective diagram 30 showing the main belts and binder-belts, together with the pulleys by which they are carried.

Referring to the reference-letters of the 35 drawings, A represents the main frame of the machine, upon which is carried a series of pulleys to receive a series of belts, all of which are driven from a main driving-shaft B.

The belts which convey the material to be 40 treated through the machine are of three types, and throughout the specification I shall denote these three as, first, the "main" belts, which are three in number; second, the "upper" binder-belt, which holds the material 45 firmly in engagement with the main belt, and, third, the "lower" binder-belt, which firmly holds the material after it has been released by the upper binder-belt.

Extending above the main frame A of the

machine are uprights A', A², and A³, in which 50 are secured shafts c', c², and c³, supporting grooved pulleys C', C², and C³, around which pass the main belts C. The uprights A² also act as a support for a shaft d', upon which is loosely mounted a grooved pulley D' to receive 55 the upper binder-belt D. The main belts C extend from the pulleys C³ under pulleys C⁴ on the shaft d' to pulleys C⁵, C⁶, and C⁷, journaled, respectively, upon shafts c⁵, c⁶, and c⁷, and thence to pulleys C⁸, C⁹, and C¹⁰, mounted 60 upon shafts c⁸, c⁹, and c¹⁰, and back again over the pulleys C', C², and C³. The upper binder-belt D after passing over the pulley D' passes to pulleys D² and D³, mounted, respectively, on the shafts c⁵ 65 and c⁶, and thence passes over a pulley D⁴, mounted upon a shaft d⁴, and under a pulley D⁵, mounted upon a shaft d⁵, to a pulley D⁶ upon the shaft c¹⁰.

The material to be acted upon is manually 70 fed to the machine at a point X and is jointly carried by the main belts and the upper binder-belt until it reaches the pulleys which are mounted upon the shaft c⁶, at which point the upper binder-belt leaves the main belts 75 and is replaced by a lower binder-belt E, which for some distance runs parallel with the main belts, passing over pulleys E', E², E³, and E⁴, mounted, respectively, upon the shafts c⁶, c⁷, c⁸, and c⁹, then over a pulley E⁵, 80 mounted upon the shaft d⁵, and under a pulley E⁶, mounted upon the shaft d⁴, to the starting-point.

It will be noticed that the arrangement of the belts is such that the upper binder-belt 85 occupies a position between two of the main belts on one side of the machine, while the lower binder-belt occupies a position on the opposite side of the machine, the reason for which will be presently explained when describing the combing mechanism.

The main belts and upper and lower binder-belts are all driven by the pulleys that they pass over, which are mounted upon the shaft c⁶, and this shaft is driven in turn from the 95 main driving-shaft B by pulleys B' and B², provided with a driving-belt B³.

The combing, which is performed at the rear

of the machine, is carried out by means of two rotary combs F and F', which are mounted upon vertical shafts f and f' and driven together by belt-wheels f² and f³, carrying a belt f⁴. Power is transmitted to the shaft f by a belt B⁴, which passes over a pulley B⁵ on the main driving-shaft B and a pulley b⁵ on the vertical shaft f. The combing, as will be noticed by reference to Figs. 1 and 3 of the drawings, is performed at one point where the main belts and the upper binder-belt pass around the pulleys carried by the shaft c⁵ and at another point where the main belts and the lower binder-belt pass around the pulleys carried by the shaft c⁷, the object of this being to free from the traveling line of bristles first on one side and then on the other any bristles which may not be of sufficient length to be firmly held by two of the main belts and one of the binder-belts during both of the combing operations. Thus, for instance, if there would pass before the first comb a number of bristles just long enough to be held from one side by two of the main belts and the one upper binder-belt they could not be removed; but after the upper binder-belt had retreated and the lower binder-belt had come into action on the opposite side these same bristles, not being of sufficient length to be caught by the second binder-belt, would under the action of the second comb be removed from the longer bristles.

At the discharging end of the machine, which is at a point Y, I provide a curved wire frame or receiver G to receive the finished product, which is carried around to this point by the main belts C and the binder-belt D. The product upon reaching the front end of the receiver G encounters a gate H, consisting of a cross-bar provided with a number of teeth or prongs, which pass between the belts C and the belt D, as well as the wires of the framework constituting the receiver G. The gate H is secured to a lever I, which is supported upon a shaft i, mounted in suitable bearings secured to the uprights A². The lever I is guided at one end in a frame h, con-

sisting of a cross-bar fastened to the uprights A³ and vertical arms or members, between which the lever I may freely slide. The opposite end of the lever I is made in the form of a handle, by which it may be operated to raise and lower the gate H. The object of this gate is to line up or level the bristles and to hold them in check until a bunch is formed, when by lifting the gate through the medium of the lever I, which is pivoted at i, the bunch will be allowed to pass into the receiver G.

Having described my invention, what I claim, and desire to secure by Letters Patent, is—

1. A machine of the character specified, comprising a series of main belts, a binder-belt adapted to travel into and out of line with the main belts, a rotary comb arranged adjacent to said belts, a second binder-belt, adapted to travel into and out of line with another part of the main belts, a rotary comb adjacent to the aligned portion of the main belts and second binder-belts and means for interrupting the travel of the bristles at or near the end of their line of travel for the purpose of bunching the same, substantially as specified.

2. A machine of the character specified, comprising a series of main belts, a binder-belt adapted to travel into and out of line with the main belts, a rotary comb arranged adjacent to said belts, a second binder-belt, adapted to travel into and out of line with another part of the main belts, a rotary comb adjacent to the aligned portions of the main belts and said second binder-belt, and a gate located beyond the point of separation of the last-named belts, and adapted to be moved into and out of line therewith, substantially as described.

In testimony whereof I affix my signature in presence of two witnesses.

BROR MAX SCHAUMAN.
